(57) **CLAIM**

The ornamental design for a ceiling fan, as shown and described.

DESCRIPTION

FIG. 1 is a top perspective view of a ceiling fan, showing my new design.

FIG. 2 is a bottom perspective view thereof, having the ceiling fan environment removed;

FIG. 3 is a top view thereof;

FIG. 4 is a bottom view thereof;

FIG. 5 is a front view thereof;

FIG. 6 is a rear view thereof;

FIG. 7 is a right-side view thereof; and,

FIG. 8 is a left-side view thereof.

Portions of the ceiling fan are shown in broken lines. Portions shown in broken lines form no part of the claimed design. The ceiling fan blades are shown with jagged broken lines which define a symbolic break for the blades. The jagged broken lines form no part of the claimed design.
